UNITED STATES PATENT OFFICE.

ALEX M. LOUGHMILLER, OF CROWELL, TEXAS.

PENHOLDER.

1,408,956.

Specification of Letters Patent.

Patented Mar. 7, 1922.

Application filed July 25, 1921. Serial No. 487,434.

To all whom it may concern:

Be it known that I, ALEX M. LOUGHMILLER, a citizen of the United States, residing at Crowell, in the county of Foard and State 5 of Texas, have invented new and useful Improvements in Penholders, of which the following is a specification.

The present invention relates to pen holders, and has for its primary object the provision of a holder from which the pen point can be easily and quickly ejected without taking hold of the point, thus protecting the fingers from being soiled.

More specifically stated, the invention embodies a spring pressed rod which is movable longitudinally through the pen holder, carrying a slide which co-operates with a wedge-shaped element arranged within the pen holder for holding the pen in position 20 for use, the slide operating to eject the pen from the holder when the rod is moved in one direction.

In carrying out the invention, I provide means whereby the tension of the spring can 25 be quickly and easily regulated from one end of the pen holder.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views and wherein:—

Figure 1 is a longitudinal sectional view through a pen holder, constructed in accordance with the present invention.

Figure 2 is a detail view of the movable rod removed from the pen holder.

Figure 3 is a transverse sectional view taken on line 3—3 of Figure 1.

Figure 4 is a detail view of the slide.

Figure 5 is a similar view of the wedge-shaped element.

Referring to the drawing in detail, 10 indicates a pen holder of usual well known construction, excepting that the holder is provided with opposed slots 10' for a purpose to be presently described. Positioned within the holder 10 is what I term a wedge element 11, this element being curved to conform to the curvature of the pen indicated

at 12. The element 11 is bifurcated to provide pointed prongs or branches 12' which are adapted to be imbedded in the pen holder 10 as illustrated in Figure 1. This element 11 is further provided with lugs 13 which project from the opposed sides of the element and pass through the slots 10' of the pen holder and through aligned slots 14 provided in a ferrule 10^a which surrounds the lower end of the pen holder 10. In this manner, the element 11 is held fixed relative to the pen holder 10.

A rod 16 is arranged longitudinally through the pen holder 10, the rod projecting from one end of this holder and threaded as at 17 to accommodate an adjusting nut 18. A spring 19 encircles this rod and bears against the nut 18 to normally hold the rod 16 projected from the small end of the pen holder. A sleeve like member 20 surrounds the pen holder for a portion of its length, and conceals from view, that portion of the rod 16 and the spring 19 which projects from one end of the holder. The opposite end of the rod 16 terminates to provide a hook-like portion 21 which is passed through an opening 22 in a slide 23, the latter being curved correspondingly with the pen 12, and the wedge-shaped member above described for a purpose to be presently set forth. The slide is actuated through the instrumentality of the rod 16, and when the rod is in its normal position, the slide is arranged within the pen holder and effectively grips and holds the pen 12 positioned for use between the slide and the wedge-shaped member. When it is desired to separate the pen from the holder, it is only necessary to depress the rod 16 against the tension of the spring, which results in moving the slide 90 from one end of the holder and at the same time ejecting the pen so that the latter will fall from the holder. In this manner, the pen can be quickly and easily ejected without touching the latter, and thus preventing 95 the hands or fingers from being soiled in the performance of this duty. It is obvious that by adjusting the nut 18, the tension of the spring can be varied from time to time as the occasion may require.

While it is believed that from the foregoing description the nature and advantages of the invention will be readily apparent, I desire to have it understood that I do not limit myself to what is herein shown and 110

described, and that such changes may be resorted to when desired as fall within the scope of what is claimed.

What I claim is:—

5 In combination, a pen holder having slots adjacent one end, a wedge-shaped element positioned within the holder, attaching lugs carried by said member and passed through said slots for holding the member fixed relative to said holder, a spring pressed rod

movable longitudinally through the holder, a slide carried by one end of the rod and normally positioned within the holder to hold the pen therebetween and said wedge-shaped member, and said slide operating to 15 eject the pen from the holder upon movement of the rod in one direction.

In testimony whereof I affix my signature.

ALEX M. LOUGHMILLER.
